(57) **CLAIM**

The ornamental design for a wall mounted cable distribution housing cover, as shown and described.

DESCRIPTION

FIG. 1 is a front perspective view of a cover for a cable distribution housing, showing our new design;

FIG. 2 is a front elevational view thereof;

FIG. 3 is a side elevational view thereof;

FIG. 4 is a top plan view thereof;

FIG. 5 is a rear elevational view thereof;

FIG. 6 is a side elevational view thereof, opposite that shown in FIG. 3;

FIG. 7 is a bottom plan view thereof;

FIG. 8 is a perspective view of the cover of FIG. 1 shown in its environment;

FIG. 9 is a front perspective view of a cover for a cable distribution housing, showing a second embodiment of our new design;

FIG. 10 is a front elevational view of the embodiment of FIG. 9;

FIG. 11 is a rear elevational view of the embodiment of FIG. 9; and,

FIG. 12 is a perspective view of the cover of FIG. 9 shown in its environment.

The broken lines shown herein are for illustrative purposes only and form no part of the claimed design.
